UNITED STATES PATENT OFFICE.

PATRICK JAMES RILEY, OF ST. LOUIS, MISSOURI.

HEEL-BUILDING MACHINE.

1,080,302.

Specification of Letters Patent.

Patented Dec. 2, 1913.

Application filed April 12, 1912. Serial No. 690,251.

To all whom it may concern:

Be it known that I, PATRICK J. RILEY, a citizen of the United States, residing at St. Louis, in the State of Missouri, have 5 invented new and useful Improvements in Heel-Building Machines, of which the following is a specification.

The present invention relates to improvements in heel building machines.

10 In carrying out my invention I propose to provide a heel-cutting die having arranged in connection therewith a tube or cylinder having a cross section shaped to correspond with that of the die and the heel-lifts cut by the die, the said cylinder being normally sustained in proper relation with the die through the medium of suitable 15 resilient elements, and the cylinder being also provided with a lift rest which is adapted to yieldably contact with the cylinder walls to support the lifts or layers of leather forming the heel, and to be moved a distance equaling the thickness of each of the said 20 lifts as the lifts are successively forced through the die and within the cylinder, the cylinder being removable whereby, the lifts which are formed into a log may be removed 25 therefrom and arranged within a suitable device where they are allowed to dry under pressure, it being understood that 30 the lifts are preferably moistened before being cut and forced into the cylinder.

I further aim to provide in a heel building machine, cylinders of various lengths, where- 35 by leather logs of any desired length may be made, the said logs after being removed from the cylinder being adapted to be cut by a knife the desired lengths.

With the above recited objects in view, 40 and others of a similar nature which will be apparent as the invention is disclosed, the improvement resides in the novel construction, combination and arrangement of parts set forth in and falling within the scope of 45 the appended claims.

In the drawings, Figure 1 is an elevation of a device constructed in accordance with the present invention, the supporting table being shown in section. Fig. 2 is a central 50 longitudinal sectional view of the same. Fig. 3 is a perspective view of the lift rest. Fig. 4 is an elevation of one of the leather logs constructed by the machine. Fig. 5 is a perspective view of a portion of the log 55 constituting the heel body. Fig. 6 is a perspective view of the die. Fig. 7 is a per-

spective view of a die and cylinder formed integrally therewith which may be employed. Fig. 8 is a vertical longitudinal sectional view through the same.

It may here be stated that the leather forming the lifts may be glued together before being operated upon by the die and cutter if desired, and it is to be understood that the strips of leather providing the lifts formed by the machine may be moistened or subjected to a bath in a suitable fluid before the same are cut, and after the said lifts are removed from the cylinder of the machine they are dried under compression 70 after which the log formed by the machine is cut with a sharp knife into proper lengths to form heels.

In the construction illustrated in the drawings (Figs. 1 to 6 inclusive), I provide 75 a table 1 which includes a top 2 as well as a bottom board 3. Arranged directly above and partly surrounding an opening provided in the top 2 of the table is a cutting member or die 5 of a desired size and shaped 80 to correspond with the heel to be manufactured by the machine.

The numeral 7 designates a suitable mal- 85 let which is adapted to coöperate with the cutting element or die 5.

Arranged below the die 5 and having its upper portion positioned within the opening of the table formed for its reception, is a cylinder 6. This cylinder or tube is of a cross sectional shape corresponding to the 90 shape of the interior of the die 5, the lower portion of the cylinder 6 being received within a recess or pocket formed in the upper face of the board or connecting member 3 of the table.

The numeral 8 designates a plurality of 95 compression springs which are retained upon the bottom face of the pocket 7' and which are adapted to exert a pressure upon the lower edge of the cylinder 6 to force the upper edge of the said cylinder tightly into contact with the lower face of the die 5. The pocket 7' is of a depth sufficient to permit of the cylinder being forced downwardly therein against the tension of the springs 8 100 to permit of the upper portion of the said cylinder being withdrawn from the opening in the top 2, the purpose of which will pres- 105 ently be apparent.

The numeral 9 designates the follower or 110 movable lift rest which is arranged within the cylinder 6. The rest comprises a pair

of sections 10 and 11 the opposing faces of which are provided with centrally disposed depressions 12 and 13 respectively, the said depressions being opposite one another and adapted to receive a coil spring 14 operating to force the members 10 and 11 tightly against the inner wall of the cylinder 6. It is to be understood that the outer edges of the members 10 and 11 correspond with the shape of the cylinder 6, and each of the said members 10 and 11 is provided upon its under face with suitable eyes 15 and 16. These eyes are arranged in pairs which are positioned diametrically opposite one another and the said eyes are adapted to receive a loosely arranged rod which preferably has its opposite ends headed as at 17 and which serves as means for preventing the entire separation of the members 10 and 11. The lift rest, while resiliently contacting with the walls of the cylinder 6 is of course, givable to permit of the said rest being advanced through the cylinder as the lifts are fed successively into the cylinder. The lifts or heel layers may be made of a single piece of material or of a plurality of pieces cut at angles to provide a complete lift as illustrated in Fig. 5 of the drawings. The lifts, which may be designated by the numerals 18, are fed either separately or in numbers to the top of the cutting member or die 5, when the plunger 7 is operated to cut the leather and to force the lifts to the cylinder 6. The lift rest 9 prevents the lifts from dropping through the cylinder which, may if desired and which preferably is of a slightly larger area than that of the die proper, in order that the log formed by the lifts may be readily removed from the cylinder. When sufficient lifts have been fed to the cylinder 6 to complete a log, the said cylinder 6 is forced downwardly against the tension of the springs 8, then slightly tilted and removed from the table and the log forced out of the cylinder and is delivered to a separate machine where the same is compressed under pressure. As heretofore stated, the separate lifts may be glued or otherwise secured together before or while being fed to the cylinder 6.

The numeral 25 designates the complementary knife member which is arranged upon the upper face of the table and which is employed in connection with the mallet 55 to cut the straight edges of the pieces of leather from which the lifts are formed.

At the beginning of the operation, the follower 9 occupies a position to bring its upper face flush with the cutting edge of the die 5. When the first piece of leather (with its straight edge cut by the knife 25) is brought under the mallet 7, the curved outer edge of said leather piece will be cut by the die, the mallet driving the said piece into the die, which thereby causes the follower

or rest 9 to advance in the tube 6 a distance corresponding to the thickness of the leather piece which thus constitutes one of the sections of the layer forming a single lift. The cutting of the remaining sections of the layer has no further effect however, in advancing the follower. When the first leather section of the layer making up the next lift is cut by the die, the mallet again advances the follower a distance corresponding to the thickness of the leather piece thus cut, and so on with successive lifts, the follower advancing a distance corresponding to the thickness of the leather piece thus cut, and so on with successive lifts, the follower advancing a distance corresponding to the thickness of a lift with the formation of such lift. The straight edges of the leather sections constituting any lift are cut by the eye on the edge of the knife 25, the mallet 7 being used to drive the piece to be cut. When the tube or cylinder 6 fills with "lifts" a heel-log will be formed, the lifts adhering together where adhesive has been used before the die is applied; otherwise the log sections are separable when removed from the cylinder. Of course, when the cylinder is full of lifts, the follower will have been forced against the springs 8. By compressing the springs sufficiently to permit the withdrawal of the upper end of the cylinder from the opening in the table-top 2 in which it normally rests, and then canting or inclining the cylinder, the same may be readily withdrawn from the pocket 7, the follower pulled out through the open bottom of the cylinder and the lifts abstracted either in a predetermined number of sections when not adhering together, or as a single log where they are glued together, depending on the mode of subsequent treatment.

The numeral 30 designates a die and cylinder made integral which may be employed. This die comprises a hollow element having an upper sharpened edge, which corresponds in shape with the heel lift and is further provided with a closed bottom 31.

From the above description, taken in connection with the accompanying drawings, the simplicity of the device, as well as the advantages thereof, will, it is thought, commend themselves to those skilled in the art to which such inventions appertain without further detailed description.

Having thus described the invention, what I claim is:—

1. In combination with a fixed support, a suitable heel-lift-forming die mounted above and discharging through, the support, a tube positioned in the path of discharge of the die for receiving the heel-lifts at one end, a follower within the tube adapted to be advanced therethrough by the successive lifts discharged from the die, a fixed

support engaging the discharge end of the tube, and resilient devices interposed between said support and said discharge end of the tube to permit retraction of the opposite end of the tube from the die.

2. In combination with a fixed support, a suitable heel-lift-forming die mounted on one side of said support and discharging therethrough, a tube mounted to form a continuation of the die but disposed on the opposite side of said support, a follower adapted to traverse the die and tube with successive accessions of lifts into the die, a second fixed support engaging the discharge end of the tube, and provided with a pocket beyond the end of the tube, and resilient devices in said pocket engaging the adjacent end of the tube, whereby upon compression thereof, the intake end of the tube may be retracted out of engagement with the first fixed support.

3. In combination with a heel-lift-forming die, a tube or cylinder leading therefrom, a follower traversing said die and tube and comprising a pair of opposed and separable sections peripherally engaging the inner walls of the die and tube, the faces adjacent

the plane of separation between the sections being provided with opposite depressions, a compression-spring confined in said depressions, suitable alining eyes on the outer faces of the respective sections, and a headed rod loosely passed through the eyes, for the purpose set forth.

4. The herein described apparatus comprising a heel lift-forming die, a tube so located as to receive the lifts from the die, yielding means for sustaining the tube against the die, a yieldable support for the lifts frictionally engaging within the tube, said support comprising a pair of sections, spring members for forcing the sections away from each other and into frictional contact with the tube, and elements loosely arranged upon the sections to prevent the entire separation of the sections.

In testimony whereof I affix my signature in presence of two witnesses.

PATRICK JAMES RILEY.
